OF SYRACUSE, NEW YORK, A CORPORATION OF NEW YORK.

CLUSTER LAMP-SOCKET.

1,076,477.

Specification of Letters Patent.

Patented Oct. 21, 1913.

Application filed March 18, 1912. Serial No. 684,369.

To all whom it may concern:

Be it known that I, CARL H. BISSELL, of Syracuse, in the county of Onondaga and State of New York, have invented a certain new and useful Cluster Lamp-Socket, of which the following is a specification.

This invention relates to incandescent electric lamp sockets and one of the objects thereof is the production of a cluster or plural lamp socket which is particularly simple in construction and highly efficient in use.

Other objects will appear throughout the specification.

The invention consists in the combinations and constructions hereinafter set forth and claimed.

In describing this invention reference is had to the accompanying drawing in which like characters designate corresponding parts in all the views.

Figure 1 is a plan of one form of my lamp socket. Fig. 2 is a sectional view on line "A—A" Fig. 1. Figs. 3 and 4 are sectional views taken on the plane of line "B—B," Fig. 2, the connection for a drop light being shown in Fig. 3 and for a switch in Fig. 4. Figs. 5 and 6 are opposing face views of the body and cap of the lamp socket.

This cluster lamp socket comprises, generally, a hollow body open at one side, a plurality of sockets associated with the body, a cap for the open side of the body, lamp contact terminals in the sockets, conductors within the body connecting like terminals of the sockets and feed or plug terminals carried by the cap and electrically connected respectively to the conductors. In the illustrated embodiment of my cluster socket, means is provided by which another electrical appliance may be connected in series with the conductors between one of the feed or plug terminals and said conductors if the appliance is a snap switch, or may be connected in multiple with the conductors, if the appliance is a lamp.

1 is the hollow body of the cluster lamp socket, the body being formed of insulation and being open at 2 at its top.

3 are sockets of insulation integral with the body and here shown as projecting in divergent directions from the body.

4 is the cap of insulation for closing the open top 2 of the body.

5 and 6 are, respectively, the central and sleeve terminals of the lamp sockets.

7 and 8 are conductors in the form of yokes connecting respectively the central terminals 5 and the sleeve terminals 6 thereof, the conductors 7 and 8 having portions arranged opposed or parallel, and the conductor 7 being arranged above the conductor 8.

9 and 10 are, respectively, the central and outer feed or plug terminals, the outer terminal being mounted on the periphery of a central, projecting, cylindrical boss 11 rising from the outer face of the cap 4. The central terminal 9 serves to hold the cap and body together and, as here shown, comprises a screw, the head of which is located on the end of the boss 11 and the lower threaded end of which turns into the threaded opening 12 of the yoke 8, the screw extending through an enlarged opening 13 formed in the yoke 7 and axially aligned with the screw threaded opening 12. Preferably the cap 4 is formed with a depending central tapered boss 14 around the lower portion of the screw 9, the boss 14 extending through said opening 13 and insulating the central terminal from the yoke 7. The outer terminal 10 is here shown as formed with a plurality of outwardly extending lugs 15 at its base which lap the outer annular face of the cap 4 around the boss 11 and through two of which, fastening screws 16 are passed, which turn into nuts 17 on the inner face of the cap 4. The third of said lugs 15 is held in position by a terminal member, as a screw 18 which is part of means to conduct the current to the yoke 7, as hereinafter explained.

19 is a terminal member, here shown as a hollow screw, paired with the screw 18 and extending through the cap 4.

20 is a terminal plate, mounted on the lower end of the screw 18 and lying against the inner face of the cap 4 and having a binding device or screw 21.

22 is a terminal plate on the lower end of the hollow screw 19, the plate having a binding device or screw 23.

24 is a spring conductor U-shape in gen-

eral outline, one branch of which is interposed between the terminal plate 22 on the inner face of the cap 4, and the other branch of which yieldingly contacts the upper face 5 of the yoke 7 and conducts the current from the screw 19 to the conductor 7.

25 is a removable link or clip electrically connecting the pair of screws 18, 19, said clip at one end extending under the head of the screw 18 and at its other end extending under the head of a screw 26 threading into the hollow screw 19.

As thus far described when the plug terminals are turned into a feed socket, the current will pass to or from the outer plug terminal 10 through one of the lugs 15, screw 18, link 25, screw 19 and conductor 24, yoke 7, terminals 5 through the lamps to the terminals 6, conductor 8 and central plug terminal 9.

27 and 28 are the opposite arms or wires of the branch circuit adapted to be connected in series between the plug terminals and the lamp terminals, or to be connected in 15 multiple with the lamp terminals. When the arms 27, 28 of the circuit are connected in series with the lamp terminals, a snap switch is attached thereto for making and breaking the circuit to the lamp terminals, 20 5, 6, and one of the arms of such circuit as the arm 27 is connected to one of the binding devices of the pair of terminal members or screws 18, 19 as the binding device 23 of the screw 19, and the other arm 28 of the branch circuit may either be connected to 25 the other binding device 21 or the screw 18 when the link 25 is removed, or may be connected to a binding device 29 projecting from the conductor 8. In the latter case the 30 branch circuit is connected in multiple with the lamps and is designed to be connected with an incandescent drop lamp. The branch circuit extends outwardly through the opening 30 located between the sockets 35 3. In order to relieve the binding devices 21, 23 and 29 of the weight of the wires 27, 28 and appliances, the wires are looped through holes 31 in the cap.

This lamp socket is particularly advantageous in that it consists of but few parts, which are easily assembled, and in that the parts are easily accessible, and further in that either a drop lamp or a snap switch may be used in connection with the socket.

55 What I claim is:

1. A cluster lamp socket comprising a hollow body open at one side, a cap for the open side of the body, conductors within the body, each connecting like terminals of the sockets associated with the body, feed terminals carried by the cap and having means for electrically and mechanically connecting one of the feed terminals to one conductor and thereby holding the cap and body together, and means electrically con-

nnecting the other of the feed terminals and the other conductor, the latter means including a member frictionally engaged with the other conductor, substantially as and for the purpose described.

2. A cluster lamp socket comprising a hollow body open at one side, a cap for the open side of the body, conductors located in the body and each coupling like terminals of the sockets associated with the body, one conductor being interposed between the other conductor and the open side of the body and having an opening therethrough, and central and outer feed terminals carried by the cap, the central feed terminal comprising a fastening member extending through the cap and through said opening in one conductor and being detachably connected to the other conductor for mechanically securing the cap and the body together, substantially as and for the purpose specified.

3. A cluster lamp socket comprising a hollow body open at one side, a cap for the open side of the body, conductors in the form of yokes located in the body and coupling like terminals of the lamp sockets together, one conductor extending between the other conductor and the cap and being formed with an opening, central and outer feed terminals carried by the cap, the central terminal extending through the cap and said opening of the conductor and being mechanically connected to the other conductor, and the cap being formed with an insulating projection extending through the opening of said conductor, substantially as and for the purpose set forth.

4. A cluster lamp socket comprising a hollow body of insulation open at its top, a cap for the open top of the body, conductors in the form of yokes extending across the interior of the body and connecting like terminals of the lamp sockets, one conductor being arranged above the other and formed with an opening, and central and outer feed terminals on the cap, the central terminal comprising a member extending through said opening of the upper conductor and being detachably connected to the lower conductor, and the cap being formed with a depending insulating boss surrounding said member and extending through the opening of the upper conductor, substantially as and for the purpose described.

5. An incandescent electric lamp socket comprising lamp contact terminals, feed terminals, conductors connected to the lamp contact terminals and to the feed terminals, and means including a shiftable part by which a branch electric circuit may be connected in series with the conductors or in multiple with said conductors between the feed terminals and said conductors, substantially as and for the purpose specified.

6. An incandescent electric lamp socket comprising lamp contact terminals, feed terminals, conductors connected to the lamp contact terminals and to the feed terminals, and means by which a branch electric circuit may be connected in series with the conductors or in multiple with said conductors between the feed terminals and said conductors, said means comprising a removable link, substantially as and for the purpose set forth.
7. In an incandescent electric lamp socket, an electrical connection between one feed terminal and one of the lamp socket terminals, the connection comprising a pair of terminal members and a removable link connecting said members, and a branch circuit, the arms of which may either be connected to the pair of terminal members upon the removal of the link or to one of said terminal members of the pair and to the other lamp socket terminal when the link is in position, substantially as and for the purpose described.
8. An incandescent electric lamp socket comprising a hollow body open at one side, a cap for the open side of the body, central and outer feed terminals carried by the cap, electrical connections between the feed terminals and the lamp socket terminals respectively, each of said connections including conductors located in the body, and one of said connections including a pair of terminal members carried by the cap between one feed terminal and the conductor of said connection, and a removable link carried by the cap and connecting the terminal members together, and a branch circuit for connection to an electric lamp or a switch, one arm of the branch circuit being adapted to be connected to one of said pair of terminal members and the other being adapted to be connected to the other conductor or to the other of said pair of terminal members upon removal of the link, substantially as and for the purpose specified.
9. A cluster lamp socket comprising a hollow body open at one side, a cap for the open side of the body, conductors in the form of yokes connecting like terminals of the lamp sockets, central and outer feed terminals carried by the cap, electrical connections between the feed terminals and the yokes respectively, the connection to one of said yokes comprising a pair of terminals extending through the cap, and a removable link located on the outer face of the cap and connected to said pair of terminals, and a branch circuit comprising wires extending through the body and adapted to be connected to a lamp or a snap switch, the wires being adapted to be connected in circuit with one yoke at one of the pair of terminals and to the other yoke or to both of said pair of terminals upon the removal of the link, substantially as and for the purpose set forth.

In testimony whereof, I have hereunto signed my name in the presence of two attesting witnesses, at Syracuse, in the county of Onondaga, in the State of New York, this 12th day of March, 1912.

CARL H. BISSELL.
